Primary Examiner—Louis S. Zarfas*Assistant Examiner*—Robin V. Taylor*Attorney, Agent, or Firm*—Harold H. Dutton, Jr.[57] **CLAIM**

The ornamental design for a trash bag retainer, as shown and described.

DESCRIPTION

FIG. 1 is a perspective view of a trash bag retainer in a closed position showing my new design;

FIG. 2 is an opened front view thereof;

FIG. 3 is a rear view thereof;

FIG. 4 is a top view thereof;

FIG. 5 is a right end view thereof; and,

FIG. 6 is a left end view thereof.

The trash bag retainer is shown fragmented in FIGS. 2, 3 and 4 for ease of illustration.
